H. HERTZBERG

SWITCH CONTROLLED ELECTRIC APPLIANCE

Filed March 9, 1922

Patented May 1, 1923.

1,453,587

UNITED STATES PATENT OFFICE.

HARRY HERTZBERG, OF BROOKLYN, NEW YORK, ASSIGNOR TO MAGNUS ELECTRIC COMPANY, INC., A CORPORATION OF NEW YORK.

SWITCH-CONTROLLED ELECTRIC APPLIANCE.

Application filed March 9, 1922. Serial No. 542,362.

To all whom it may concern:

Be it known that I, HARRY HERTZBERG, a citizen of the United States of America, residing in the city of New York, borough of Brooklyn, county of Kings, and State of New York, have invented certain new and useful Improvements in Switch-Controlled Electric Appliances, of which the following is a specification.

10 This invention relates generally to switch controlled electrical appliances such as attachment plugs and has specific reference to switches of the type particularly adapted to be used in connection with such plugs.

15 An important object of the invention is to so construct and arrange the various elements embodied therein, as to make possible the provision of a compact and durable device employing an improved form of switch which is inexpensive to manufacture and reliable in operation.

20 Other objects of the invention and certain advantages thereof will become apparent from the following description taken in connection with the accompanying drawings in which:

Figure 1 is a plan view of a switch plug embodying my invention.

25 Figure 2 is a view showing in elevation the internal construction of the plug.

Figure 3 is a transverse sectional view taken on line 3—3 of Figure 2.

30 Figure 4 is a longitudinal sectional view taken on line 4—4 of Figure 2.

Figure 5 is a similar view to that of Figure 4 taken on line 5—5 of Figure 2.

35 Figure 6 is a perspective view of a reciprocating or circuit closer operating bar.

Figure 7 is a plan view illustrating the 40 circuit closer as about to snap from opened to closed position.

In the drawings wherein I have shown what I at present consider the preferred 45 form of my invention, the numeral 5 indicates a housing or casing formed of suitable insulating material, the casing being composed of two similar sections 6 and 7 which are arranged in a face to face relation and held in position by means of screws or bolts 50 8 passed transversely through the section. Each of the sections 6 and 7 is so formed or moulded as to provide registering chambers 9 and 10, within which are arranged gripping contacts 11 and 12, which respectively comprise resilient fingers 13 and 14

to which are connected similar fingers 15 and 16. The sections 6 and 7 are constructed to provide also a switch chamber 17 within which is arranged a snap switch, indicated as a whole by the numeral 18.

The switch 18 comprises a base or switch block 19 formed from suitable insulating material, to the upper face of which is secured a pair of resilient substantially U-shaped contact members 20 and 21. These resilient contact members are held in position respectively by means of screws 22 and 23, the screw 22 being utilized to electrically connect the gripping contact 12 with the resilient contact 20, whereas the screw 23 is utilized to electrically connect the resilient contact 21 with a relatively short conductor 24, the outer or free end of which is held in position within the recess 25 formed in the section 7 by means of a screw 26. It will be noted that the gripping contact 11 is provided with an extension 27 which passes under the switch block 19 and terminates within the recess 28 formed in the section 7, the extension 27 being secured 70 at its free end to the section 7 by means of a screw 29. The screws 26 and 29 are adapted also to electrically connect the bared ends of conductors 30 and 31 with the conductor 24 and the extension 27. As a means for 75 protecting the conductors 30 and 31 there is provided the usual form of flexible coil 32 which is suitably held at one end between the sections 6 and 7.

As a circuit closer operating means I 80 employ a reciprocating bar 33 which is adapted to operate in a transverse groove 34 formed in the base 19. The bar 33 is provided at opposite ends with push buttons 35 which extend through openings 36 formed in the sections 6 and 7 and are adapted to operate within recesses 37 formed in the base 19. Upon the upper face or edge of the bar 33 there is formed a lug 38 carrying a circuit closer in the form of a transversely 100 disposed coil spring 39 upon the ends of which are fitted a pair of contact points 40, the ends of which are tapered as shown in Figure 6. As a means for temporarily restraining the contact points against movement as the bar 33 is moved in either direction, I provide a yoke 41 the ends or arms 42 of which extend an appreciable distance above the upper face of the block 19. The yoke 41 is loosely arranged within a 110

groove 43 formed on the under face of the base 19, and is free to slightly move longitudinally in one direction or the other in order that the impinging effect of the contacts 40 upon the arms 42 thereof may be equalized to insure simultaneous engagement or disengagement between the contacts 40 or the resilient contacts 20 and 21 when the bar 33 is moved in either one direction or the other.

With the various elements positioned as shown in Figure 2, the circuit is closed through resilient contacts 20 and 21 by means of the transversely disposed coil spring 39 which functions as a conductor when the contacts 40 are electrically connected with the resilient contacts. By moving the bar 33 a tension is set up within the spring 34 tending to sever engagement of the contacts 40 with the resilient contacts 20 and 21 but such disengagement is prevented by the upwardly extending arms 42 until the bar 33 has moved a sufficient distance to enable the contacts 40 to freely pass the retarding arms 42. As soon as the spring 39 has been distorted sufficiently to permit disengagement of the contacts 40 with the arms 42, the contacts by reason of the tension maintained within the spring 39 are quickly snapped from engagement with the resilient contacts 20 and 21 thus opening the circuit therebetween. With the circuit open and the contacts 40 now located upon the opposite sides of the arms 42 the resilient contacts 20 and 21 may be placed in electrical connection with each other by a quick snap action of the spring 39 when the bar 33 is moved in an opposite direction a sufficient distance to enable the contacts 40 to freely pass the upwardly projecting arms 42.

Having thus described my invention, I claim:

1. In an electrical appliance, a pair of contacts, a movable circuit closer carrying element, a circuit closer carried by said element and adapted to be moved bodily therewith toward said contacts, and means lying in the path of travel of said closer for restraining the ends of the same against movement while said element is being moved a predetermined distance, the ends of said closer being released upon continued movement of said element and thereafter snapped into electrical connection with said contacts.

2. In an electrical appliance, a pair of contacts, a movable circuit closer carrying element, a resilient circuit closer adapted to be moved bodily by said element toward said contacts, and means lying in the path of travel of said closer for restraining the ends of the same against movement while said element is being moved a predetermined distance, the ends of said closer being released upon continued move-

ment of said element and thereafter snapped into electrical connection with said contacts.

3. In an electrical appliance, a pair of contacts, a reciprocating circuit closer operating element, a circuit closer carried by said operating element, said closer being in the form of a spring adapted to be moved bodily toward said contacts by said operating element upon a corresponding movement of the same, and means lying in the path of travel of said closer for restraining the ends of the same against movement while said operating element is being moved a predetermined distance, the ends of said closer being released upon continued movement of said operating element and thereafter snapped into electrical connection with said contacts.

4. In an electrical appliance, a pair of contacts having resilient arms, a movable circuit closer operating element, a resilient circuit closer carried by said element and adapted to be moved bodily therewith toward said contacts, and means lying in the path of travel of said closer for restraining the ends of the same against movement while said operating element is being moved a predetermined distance, the ends of said closer being released upon continued movement of said operating element, and thereafter snapped into electrical connection with the resilient arms of said contacts.

5. In an electrical appliance, a pair of contacts, a movable circuit closer operating element, a circuit closer carried by said operating element and adapted to be moved bodily therewith, said closer being in the form of a coil spring, contacts carried at the opposite ends of said spring, and means lying in the path of travel of said closer for restraining the second named contacts against movement while said operating element is being moved a predetermined distance, the second named contacts being released upon continued movement of said operating element and thereafter snapped into electrical connection with the first mentioned contacts.

6. In an electrical appliance, a base, a reciprocating closer operating element, a pair of contacts, a resilient circuit closer carried by said operating element and adapted to be moved bodily therewith toward said contacts when said element is moved in a corresponding direction, a yoke having arms lying in the path of travel of said closer for restraining the ends of the same against movement while said operating element is being moved a predetermined distance, the ends of said closer being released from said arms upon continued movement of said operating element and thereafter snapped into electrical connection with said contacts.

7. In an electrical appliance, a contact, a movable closer operating element, a circuit closer carried by said element and adapted to be moved bodily therewith toward said contact, and means lying in the path of travel of said closer for restraining an end of the same against movement while said operating element is being moved a predetermined distance, the end of said closer being released upon continued movement of said operating element and thereafter snapped into electrical connection with said contact.
8. In an electrical appliance, a pair of contacts, a reciprocating closer operating element, a resilient circuit closer carried by said element and adapted to be moved bodily therewith toward said contacts, movable means lying in the path of travel of said closer for restraining the ends of the same against movement while said operating element is being moved a predetermined distance, the ends of said closer being released upon continued movement of said operating element and thereafter snapped into electrical connection with said contacts.
9. In an electrical appliance, a pair of contacts, a circuit closer operating element, a closer carried by said element, said closer being in the form of a coil spring attached to said element and adapted to be moved
- bodily therewith toward said contacts, and means lying in the path of travel of said closer for engaging and retaining the ends thereof in a given position during a predetermined movement of said element, whereby tension is set up within said closer, the ends of said closer being released upon continued movement of said operating element and thereafter snapped into electrical connection with said contacts by the tension set up within said spring.
10. In an electrical appliance, a pair of contacts, a reciprocating circuit closer operating element having a lug carried thereby, a circuit closer in the form of a spring passed through said lug and adapted to be moved bodily with said operating element toward said contacts upon a corresponding movement of said operating element, and movable means lying in the path of travel of said closer for engaging and retaining the ends of said spring against movement while said operating element is being moved a predetermined distance, the ends of said spring being released upon continued movement of said operating element and thereafter snapped into electrical connection with said contacts.

In testimony whereof, I have affixed my signature to this specification.

HARRY HERTZBERG.
